TRAVELING BAG OR SIMILAR ARTICLE

Ira R. Katz, Nashville, Tenn., assignor to Hartmann
Luggage Company, Lebanon, Tenn.

Filed May 7, 1971, Ser. No. 141,467

Term of patent 7 years

Int. Cl. D3—01

U.S. Cl. D87—5

FIG. 1 is a front elevational view of a traveling bag or similar article showing my new design;

FIG. 2 is a view looking at the right-hand end of the bag of FIG. 1;

FIG. 3 is a rear elevational view;

FIG. 4 is a view looking at the left-hand end of the bag of FIG. 1;

FIG. 5 is a top view; and

FIG. 6 is a bottom view.

I claim:

The ornamental design for a traveling bag or similar article, as shown.
